UNITED STATES PATENT OFFICE.

JAMES M. RUDE, TO COVINGTON, KENTUCKY, ASSIGNOR TO CAN CONSERVATION COMPANY, OF LOUISVILLE, KENTUCKY, A CORPORATION OF DELAWARE.

CAN-TREATING APPARATUS.

1,340,408.

Specification of Letters Patent. Patented May 18, 1920.

Application filed March 4, 1918. Serial No. 220,213.

To all whom it may concern:

Be it known that I, JAMES M. RUDE, a citizen of the United States, residing at Covington, in the county of Kenton and State of Kentucky, have invented certain new and useful Improvements in Can-Treating Apparatus; and I do hereby declare the following to be a full, clear, and exact description of the invention, such as will enable others skilled in the art to which it appertains to make and use the same.

This invention relates to improvements in mechanism for the treating of used cans for adapting them for re-use, and has as its primary object the provision of means for cutting away a section of the bead of a can to enable the can to be severed intermediate its ends.

With this and further objects in view as will in part hereinafter become apparent and in part be stated, the invention comprises certain novel constructions, combinations and arrangements of parts as subsequently specified and claimed.

In the accompanying drawings,—

Figure 1 is a view partly in elevation and partly in vertical section of an apparatus embodying the features of the present invention.

Figs. 2, 3 and 4 are vertical sections taken, respectively, on the planes indicated by lines 2—2, 3—3, and 4—4 of Fig. 1.

Fig. 5 is a horizontal section taken on the plane indicated by line 5—5 of Fig. 1, and looking downwardly.

Referring to the drawings by numerals, 1 indicates an appropriate standard or frame in which is slidably mounted a cross head 2 to which is swiveled a supporting downwardly-extending threaded shaft 3. A worm gear 4 is appropriately housed in the frame 1 and threaded onto the shaft 3 in position for causing the shaft to move longitudinally when the worm gears revolve. A worm shaft 5 is journaled in the frame 1 and provided with a thumb head or other operating connection 6, the shaft being formed with a worm 7 meshing with the gear 4, so that the said gear may be revolved for shifting the cross head 2 up or down as may be found desirable. The cross head 2 is formed with a transverse

aperture 8 for receiving a bar 9 and the bar and aperture are preferably polysided so as to prevent the bar from revolving. Bosses 10, 10 outstand from the cross head for increasing the bearing support for the bar 9, the said bosses being formed with bores continuous of the aperture 8. A set screw 11 penetrates one of the bosses 10 and engages the bar 9 for retaining the same against moving longitudinally but allowing the bar to be adjusted longitudinally by loosening and re-setting the set screw. 65 The bar 9 is provided with graduations 12 indicating the extent of adjustment according to the length of the can to be treated.

The outer end portion of bar 9, that is 70 the end more remote from frame 1, is engaged by a sleeve 13 locked in place by a set screw 14. Upstanding from the sleeve 13 is a plate 15 which is adjustably engaged by a plate 16, the latter being formed with a slot 17 and a pin or bolt 18 engages the plate 15 and extends through the slot 17, the bolt being engaged by a nut for locking the plates 16 and 17 at any desired point of adjustment. The extreme upper 80 end portion of plate 16 is formed with a notch 19 proportioned and located for snugly receiving the longitudinal internal bead 20 of the can 21 which is to be operated upon. The bead 20 is the usual lock 85 seam of an ordinary can.

The forward portion of the can 21 is supported on framework carried by the bar 9. The said framework may assume various forms, and preferably consists of a 90 pair of sleeves 22, 22, from which upstand bars 23 bifurcated to form arms 24, 24. One arm of each bar 23 is connected with the corresponding arm of the other bar 23 by a yoke-shaped bar 25, and the other 95 two arms are correspondingly connected, each of the yoke-shaped bars 25 being adjustably mounted in sockets in the respective arms 24 and locked therein by set screws 26. A set screw 27 is passed through 100 one of the sleeves 21 and engages the bar 9 to hold the framework against longitudinal shifting. The yokes 25 are located to sustain the can in proper position for being operated upon and are adjusted by 105 manipulation of set screws 26 according

to the size of can to be treated. This adjustment is proportioned to the adjustment of the shaft 3 and it should be noted that these adjustments may be made within 5 certain limitation and when cans of a greater variation than those provided for are to be treated, the bar 9 is withdrawn and turned over to the position indicated in dotted lines in Fig. 1. The bar 9 is 10 formed with an offset bend 9' which thus provides for accommodating a different series of sizes of cans when in one position than when in another position. When the bar 9 is turned over as indicated in dotted 15 lines, I provide a new set of yokes 25 and a new plate 16 proportioned to enable taking advantage of the new range of adjustments.

Journaled in the upper portion of the 20 frame 1 is a shaft 27 driven by a pulley 28 and belt 29 or other appropriate driving mechanism not shown. An emery wheel or other abrader 30 is fixed to the end of the shaft 27 and has its upper portion extending 25 between the yokes 25 so that a can passed over the plate 16 and along the yokes 25 will be caused to surround the wheel 30. An operating lever 31 is pivoted at 32 to the frame 1, the pivot being preferably mounted 30 in a pair of ears upstanding from the frame. Lever 31 is provided with a short elbow 33 projecting below the upper portion of the frame 1 for limiting the possible extent of upward movement of the free end of lever 35 31. A spring 34 is interposed between the lever 31 and the upper portion of frame 1, so as to sustain the free end of lever 31 in a raised position and a set screw 35 is passed through a portion of lever 31 in position 40 for engaging the frame 1 to limit the downward movement of the free end portion of lever 31. A projection 36 extends downwardly from lever 31 in position to strike the can 21 along the line of its bead 20 immediately above the wheel 30. The projection 36 extends along the lever 31 a distance 45 equal to the width of the wheel 30 so that when the lever 31 is pressed down toward the can the projection 36 will engage the can 50 and spring the walls thereof sufficiently to cause the bead 20 to be depressed against the cutting surface of the wheel 30. This pressure is maintained until the wheel has cut away all of the bead and left only one thickness 55 of wall of the can. When this point is reached, the lower end of the set screw 35 strikes the upper portion of frame 1 and prevents further descent of lever 31. When the bead 20 has been removed with the exception 60 of the last thickness so that but a single thickness of wall remains, the lever 31 is released by the operator and the spring 34 lifts it sufficiently above the can to allow the can to be withdrawn. The walls of the can 65 spring away from the wheel 30 and the can

is manually slid off from its engagement with the yokes 25 and the plate 16. It is to be observed that the engagement of the bead 20 with the aperture 19 prevents revolving of the can during the grinding operation. 70

After the bead has been cut away as described, the can may be severed somewhere in the planes of the cut away portion, whereby a shorter can is produced or where the can is of sufficient length two short cans may 75 be produced. This operation is particularly desirable where some injury has occurred near the opened cover of the can and a section of the can can be removed to leave only the good part of the can for future use. 80

What I claim is:—

1. In can treating apparatus, the combination with an abrader, of adjustable can sustaining means adjacent thereto, and means for pressing the bead of a can mounted on 85 said sustaining means laterally against the abrader.

2. In can treating apparatus, the combination with an abrader, of a lever movable toward and away from the abrader and adapted to engage and press the longitudinal bead of a can laterally toward the abrader, and means for limiting the movement of the lever. 90

3. In can treating apparatus, the combination with an abrader, of a lever movable toward and away from the abrader and adapted to engage and press the longitudinal bead of a can laterally toward the abrader, and means for limiting the movement of the lever toward the abrader for limiting the extent of action of the abrader on the bead and preventing cutting of the bead after the abrader has removed all but one thickness of the wall of the can at the bead. 100

4. In can treating apparatus, the combination with an abrader, of a can support adjustable relative thereto, a worm gear for adjusting the support, and means for pressing a portion of the can sustained by the support laterally toward the abrader. 110

5. In can treating apparatus, the combination with an abrader, of a can sustaining framework, an adjustable cross head carrying the same and adapted to be shifted for moving the framework relative to the abrader, a worm gear for shifting the cross head, and means for pressing a portion of a can sustained by the framework toward the abrader. 115

6. In can treating apparatus, the combination with an abrader, of a supporting bar, a plate sustained thereby having an aperture for receiving the bead of a can to be treated, a can sustaining framework carried by the bar at opposite sides of the abrader, and means for pressing a portion of the bead of a can mounted on the framework toward the abrader. 125

7. In can treating apparatus, the combina- 130

tion with a support, of a shaft journaled therein, an abrader carried by the shaft, a framework sustained by the support adjacent the abrader and adapted to sustain a can surrounding the abrader, and means for pressing a portion of the can laterally toward the abrader.

In testimony whereof I affix my signature in the presence of two witnesses.

JAMES M. RUDE.
